POLISHING DEVICE

Angelo J. Barbato, Fort McPherson, Ga.

Application April 23, 1949, Serial No. 89,226

3 Claims. (Cl. 15—131)

1

This invention relates to a polishing device, and more particularly to a device having a handle carrying a novel head for polishing and scrubbing floors, woodwork and other finished surfaces.

An object of my invention is to provide an improved polishing device for dispensing oil, liquid wax and other polishing and cleaning materials.

Another object of my invention is to provide a polishing device with improved means for holding cans and containers of various shapes and dispensing cleaning and polishing materials therefrom.

Another object of my invention is to provide a polishing device having improved means for connecting containers of cleaning and polishing materials to the dispensing head.

Another object of my invention is to provide a polishing device having improved valve means for controlling the dispensing of various fluids.

Another object of my invention is to provide a polishing device having an improved head.

Another object of my invention is to provide a polishing device which is attractive in appearance, simple in design, rugged in construction, inexpensive to manufacture, economical in upkeep, easy to repair and efficient in operation.

Other and further objects and advantages of my invention will be apparent from the following description taken in connection with the accompanying drawing in which like characters of reference designate corresponding parts throughout the several views, and wherein:

Fig. 1 is a cross-sectional side view of a polishing device embodying my invention.

Fig. 2 is an enlarged cross-sectional view of a detail.

Fig. 3 is a front view of a detail shown in Fig. 1 with parts broken away.

Fig. 4 is a detail front view of a modified form.

Fig. 5 is a cross-sectional view of a detail.

In the embodiment chosen for illustration, a member forming a laterally elongated head 10 is attached to a handle 11. The handle 11 is formed from a hollow tube and is flattened at its lower end 11' and bent at an angle for attachment to the head 10 by means of bolt 12 and nut 13, the bolt 12 passing through a hole in the flat top portion of the head 10. A spout 14 having an elbow bend is formed of a hollow tube and threaded at its lower end which projects downwardly through the flattened end portion 11' of the handle and through the top portion of the head 10 into the interior thereof, and it

2

is held in place on the head 10 by nuts 15, 15' which also aid in holding the head 10 firmly onto the handle.

The spout 14 is provided at its upper end with a mouthpiece 16 which may be formed of rubber or other soft material adaptable to permit the mouthpiece to accommodate itself to container openings of various sizes. A fastening member 17 is slidably mounted on the handle 11 for engaging and holding the bottom of the container 18 for cleaning or polishing fluid when it is inverted and placed in use on the device. The fastening member 17 is provided with a thumb screw 19 for tightening it in place on the handle 11 at the proper place to accommodate the particular size of container being used.

The mouthpiece 16 is resilient and sufficiently spongy or springy to fit over various sizes of dispensing necks customarily provided on containers, and the large central bore of the mouthpiece may be threaded as at 20 to assure a snug fit. The spout 14 is swingably mounted on the head so that the mouthpiece 16 can be swung into position to fit over differently located dispensing necks of any of the ordinary containers, whether their cross-section be round, square or oblong.

My polishing device may be inverted to place a container of liquid material against the fastening members 17; and, when the mouthpiece 16 has been properly positioned about the dispensing opening and the slideable fastening member 17 locked in place, the head may be lowered for operation.

Fig. 1 controls the flow of fluid from the spout 14. The valve 21 is formed of a strip of flexible material, such as spring steel, and has one end anchored on the bolt 12 so as to press the valve firmly against the end of the spout 14 to close it. In order to form a more perfect fit, a piece of rubber or other soft material 22 may be wrapped around the valve so as to engage the end of the spout and close it.

Mounted in the hollow handle 11 is a valve control rod 23 which projects near the upper end of the handle and is provided with a thumb piece 24. The lower end of the valve control rod 23 projects into the head 10 and rests upon the free end of the valve 21. Pressure upon the thumb piece 24 will cause the valve control rod 23 to spring the valve 21 downward and open the spout 14 to permit liquid in the container 18 to flow through the spout. When the pressure on the thumb piece 24 is released, the valve 21 will spring to closed position and force the valve

control rod 23 upward. Pin 25 through the valve control rod beneath the top of head 10 prevents the valve control rod from being accidentally withdrawn from the handle.

When the valve 21 is opened so that liquid flows from the spout 14, it spreads out over the floor plate 26 and passes through the perforations therein onto the cloth 27 spreading and rubbing it onto the floor or other surface being cleaned or polished. The floor plate 26 is removably held in place, as a closure for the bottom of the head, by means of spring clips 28 provided on each end of the floor plate and which clip over the top of the head 10, as shown in Fig. 3. The cloth 27 has its edges folded over the upturned edges of the floor plate and is caught between the floor plate and the head 10 and held firmly in place when the floor plate is clamped to the head.

It will be readily seen that all parts of my polishing device are easily accessible for repair and cleaning. Various types of attachments can be used for cleaning or polishing, as for example the brush 29 shown in Fig. 4 can be readily snapped in place in lieu of the floor plate 26 and cloth 27. Also, the angle at which the head 10 is attached to the handle 11 can be easily and quickly adjusted by bending the flattened portion 11' of the handle.

Many modifications and adaptations will suggest themselves to those skilled in the art, and it is obvious that many changes can be made in the embodiment shown without departing from the scope of my invention as defined in the appended claims.

I claim:

1. In a device of the class described, a hollow handle, said handle having a flattened end portion bent at an angle to the body of said handle, a laterally elongated head, means for attaching said head to said flattened end portion, a fastening member on said handle, a container for fluid positioned below said fastening member and held in place thereby, said container having an externally threaded fluid dispensing neck, a tubular spout having an elbow bend and a threaded lower end, said threaded lower end extending through said flattened end portion of said handle and into the interior of said elongated head, means adjustably attaching said spout to said head and arranged to assist in holding said head onto said handle, a resilient mouthpiece mounted on the upper end of said spout and having an internally ribbed longitudinal bore fitted over said dispensing neck, a valve arranged to control the flow of fluid from said container through said spout, said valve comprising a strip of flexible material pressed against the lower end of said spout by said means for attaching said head to said handle, soft material on said valve to form a valve seat, a valve control rod extending through said handle, and polishing means removably secured to the bottom of said elongated head.

2. In a device of the class described, a hollow handle, said handle having a flattened end portion bent at an angle to the body of said handle, a head, means for attaching said head to said flattened end portion, a fastening member on said handle, a container for fluid positioned below said fastening member and held in place thereby, said container having a fluid dispensing neck, a tubular spout having an elbow bend and a lower end extending through said flattened end portion of said handle and into the interior of said head, means adjustably attaching said spout to said head and arranged to assist in holding said head onto said handle, a resilient mouthpiece mounted on the upper end of said spout and having an internally ribbed longitudinal bore fitted over said dispensing neck, a valve arranged to control the flow of fluid from said container through said spout, said valve comprising a strip of flexible material pressed against the lower end of said spout by said means for attaching said head to said handle, a valve control rod extending through said handle, and polishing means removably secured to the bottom of said head.
3. In a device of the class described, a hollow handle, said handle having a flattened end portion bent at an angle to the body of said handle, a head, means for attaching said head to said flattened end portion, a fastening member on said handle, a container for fluid positioned below said fastening member and held in place thereby, said container having a fluid dispensing neck, a tubular spout having an elbow bend and a lower end extending through said flattened end portion of said handle and into the interior of said head, means for attaching said spout to said head and arranged to assist in holding said head onto said handle, a resilient mouthpiece mounted on the upper end of said spout and having an internally threaded longitudinal bore fitted over said dispensing neck, a valve arranged to control the flow of fluid from said container through said spout, a valve control rod extending through said handle, and polishing means removably secured to the bottom of said head.

ANGELO J. BARBATO.
